UNITED STATES PATENT OFFICE

STACY B. HASELTINE, OF CHICAGO, ILLINOIS, ASSIGNOR TO W. H. MINER, INC., OF CHICAGO, ILLINOIS, A CORPORATION OF DELAWARE

CAR CONSTRUCTION

Application filed December 19, 1929. Serial No. 415,172.

This invention relates to improvements in car construction.

One object of the invention is to provide a simple, efficient and reliable combined locking and center pin for body and truck bolsters of railway cars, which may be readily applied and removed and which is adjustable to compensate for wear.

A more specific object of the invention is to provide a pin of the character described in the preceding paragraph comprising a one piece, solid pin member headed at one end to provide shouldered engagement with one of the bolsters and having a detachable key member extending through the other end for connecting the same to the other bolster, the compensation for wear being obtained by adjustable means cooperating with the key and having shouldered engagement with the corresponding bolster.

Other objects of the invention will more clearly appear from the description and claims hereinafter following.

In the drawing, forming a part of this specification, Figure 1 is a top plan view of a body bolster of a railway car illustrating my improvements in connection therewith. Figure 2 is a vertical, sectional view through the body and truck bolsters corresponding substantially to the line 2—2 of Figure 1, the upper end of my improved center pin being shown in section and the lower part in elevation. And Figure 3 is an elevational view of an adjusting member employed in connection with my improved center pin.

In said drawings, 10 designates the body bolster and 11 the truck bolster of a railway car. The body bolster is provided with the usual depending bearing projection 12, which engages a bearing seat on a bearing block 13 mounted in a pocket 14 at the top of the truck bolster. The cooperating bearing surfaces of the projection 12 and the block 13 are preferably of spherical shape. The bearing block is also provided with the usual upstanding annular rib 15, which engages within a seat 16 in the bearing projection 12 of the body bolster. The body bolster, the truck bolster and the bearing block 13 are provided with the usual aligned pin receiving openings

indicated by 17, 18 and 19. The pin receiving openings 17, 18 and 19 are preferably of circular cross section and of the same diameter. Below the pin receiving opening 18, the truck bolster is provided with a pocket 55 119 defined by the spaced vertical webs 20—20 of the bolster. The pocket 119 is of greater width than the diameter of the pin receiving opening 18, thus providing a retaining shoulder 21 adjacent the outer end of 60 said opening.

My improved combined locking and center pin means comprises broadly a center pin A, a sleeve B and a key C.

The pin A is of one piece construction and 65 comprises a cylindrical shank portion 22 and a head member 23 at the bottom end thereof. The shank 22 of the pin A is transversely slotted adjacent the upper end, as indicated at 24. The slotted end of the pin extends into 70 a pocket 25 provided in the body bolster immediately above the pin receiving opening 17 thereof. The pocket 25 is preferably of circular cross section and of considerably greater diameter than the pin receiving 75 opening 17, thereby providing an annular shoulder 26 at the bottom of said pocket immediately adjacent the upper end of the opening 17. The opposed side walls of the pocket 25 are vertically slotted, as indicated 80 at 27—27, the slots 27—27 being in alignment and at diametrically opposite sides of said pocket.

The adjusting means B of my improved center pin construction is in the form of a 85 cylindrical sleeve, as most clearly shown in Figure 3. The sleeve B is of such a size that it fits over the upper end of the shank of the member A and is accommodated between the same and the cylindrical wall of the pocket 90 25 and rests on the shoulder 26. The sleeve B is provided with a plurality of sets of diametrically aligned slots 28—28, 29—29 and 30—30. The pair of slots 29—29 is arranged at a higher elevation than the slots 28—28 and the pair of slots 30—30 is arranged at a still higher elevation than the slots 29—29.

The pin member A is connected to the sleeve B by the key C, which extends through the 100

key slot 24 of the pin A and one of the pairs of alined slots of the sleeve B. As shown in the drawings, the key is engaged within the pair of slots 28—28. As will be evident, when the sleeve is turned with respect to the pin member A, either of the other two pairs of slots may be brought into alinement with the key receiving opening 24 of the pin to receive the key C. Inasmuch as the slots 29—29 and the slots 30—30 are at different elevations than the slots 28—28, insertion of the key within either of these two sets of slots will effect elevation of the lower end of the pin and bring the head 23 thereof closer to the shoulder 21 of the truck bolster, thus shortening the effective length of the pin. This adjustment is important to take up for wear which occurs between the parts. The key C is of such a length that it extends through the slots 27—27 in the wall of the pocket 25 and projects some distance beyond the wall at the righthand side of the pocket, as viewed in Figure 2. Accidental removal of the key C is prevented by a retaining bolt 31 extending through the projecting end of the key and through alined vertical slots 32—32 provided in spaced webs 33—33 on the body bolster, as clearly shown in Figures 1 and 2. Upon reference to Figure 2, it will be seen that the slots 27—27 are of considerably greater height than the slots in the sleeve B, thereby permitting vertical displacement of the key in making the different adjustments. The slots 32—32 of the webs 33—33 accommodate upward movement of the bolt 32 for this adjustment of the key. In order to support the pin on the truck bolster, a shelf 34 is preferably provided. This shelf is in the form of a flanged plate having horizontal section on which the head of the bolt rests, and spaced vertical sections in the form of flanges at opposite ends thereof which are riveted to the webs 20—20 of the truck bolster. In applying my improved combined locking and center pin means to the bolsters of a railway car for connecting the same, the pin A is inserted upwardly through the opening of the truck bolster into the body bolster. When the pin has been completely inserted, the shelf 34 may be applied and riveted to the webs of the truck bolster. The sleeve B may then be placed within the pocket of the body bolster about the upper end of the shank of the pin with the proper pair of slots alined with the key receiving opening of the pin and the slots 27—27 of the body bolster so as to obtain the desired adjustment in length of the pin. The key C is then inserted through the alined slots of the sleeve and pin member A by entering the same through one of the openings or slots 27 of the body bolster. After having been engaged within the slots, the key is secured against removal by the retainer bolt 31.

65 In this connection, it is pointed out that

in assembling the parts of the combined locking and center pin members with the bolsters, the sleeve B may be inserted within the pocket of the body bolster before the pin A is entered through the opening of the truck bolster. It is further pointed out that the shelf 34 need not necessarily be employed and that the parts may be assembled by first placing the sleeve B within the pocket 25 of the body bolster, then entering the pin through the opening of the truck bolster and immediately engaging the key C within the proper openings of the sleeve B and the pin A. When it is desired to separate the bolsters, it is merely necessary to remove the key C, whereupon the body bolster may be elevated with respect to the truck bolster. In case it is found necessary to remove the pin, the shelf 34 is detached and the pin dropped through the pin receiving openings of the bolsters after removal of the key C.

The adjusting sleeve B provides for six different adjustments. The three sets of slots being spaced different distances from the top and bottom ends, the sleeve may be reversed or inverted end for end, thereby obtaining three adjustments when in the position shown in Figure 3 of the drawings and three additional adjustments when inverted.

I have herein shown and described what I now consider the preferred manner of carrying out my invention, but the same is merely illustrative and I contemplate all changes and modifications that come within the scope of the claims appended hereto.

I claim:

1. In car construction, the combination with body and truck bolsters provided with alined center pin receiving openings; of a center pin extending through said openings and having shouldered engagement at one end with one of said bolsters to prevent removal of the pin in one direction; and means extending through the free end of the pin and bearing on an adjustable member having shouldered engagement with the other bolster to prevent removal of the pin in the opposite direction.

2. In car construction, the combination with body and truck bolsters provided with alined center pin receiving openings; of a solid center pin extending through said openings, said pin having a head at one end, the head having shouldered engagement with one of the bolsters to prevent removal of the pin in one direction; a removable key extending through the opposite end of the pin; and an adjustable member surrounding the shank of the pin interposed between the key and an abutment surface on the other bolster, thereby preventing removal of the center pin in a reverse direction, said adjustable member having shoulders at different elevations with which said key member is engageable to effect adjustment of the pin to compensate for wear.

3. In car construction, the combination with body and truck bolsters having alined center pin receiving openings; of a solid pin connecting said bolsters, said pin comprising a shank portion disposed in said alined openings and an integral head of larger diameter than said openings, said head engaging one of the bolsters to prevent removal of the pin in one direction; means for preventing removal of the pin in a reverse direction comprising a locking element extending through the pin and protruding laterally beyond the walls of the opening in the corresponding bolster; and a ring surrounding the shank of the pin, said ring having engagement with the other bolster and having a series of seats at different elevations for said locking element.

4. In car construction, the combination with body and truck bolsters having alined center pin receiving openings, each bolster having a shoulder adjacent the outer end of its opening; of a center pin extending through said openings, said pin having a head member at one end having shouldered engagement with one of said bolsters; a sleeve member surrounding the shank of the pin at the other end thereof and bearing on the shoulder of the other bolster, said sleeve having a plurality of sets of diametrically opposed seats, said sets being staggered with respect to each other; and a key extending through the last named end of the pin and having its opposed ends engaged with one of said sets of diametrically alined seats of the sleeve.

5. In car construction, the combination with body and truck bolsters having alined center pin receiving openings, each of said bolsters having a shoulder adjacent the outer end of its opening; of a center pin extending through said openings, said pin having a head at one end, and a transverse key receiving slot at the other end; a sleeve surrounding said slotted end of the pin, said head and sleeve having engagement respectively with the shoulders of said bolsters, said sleeve having a set of diametrically alined key receiving slots disposed at one level and a second set of diametrically alined key receiving slots disposed at a different level; and a key for connecting the sleeve and pin, said key being engaged within the key slot of the pin and either set of slots of the sleeve.

6. In car construction, the combination with body and truck bolsters having alined center pin receiving openings, each of said bolsters having a shoulder adjacent the outer end of its opening; of a center pin extending through said openings, said pin having a head at one end, and a transverse key receiving slot at the other end; a sleeve surrounding said slotted end of the pin, said head and sleeve having engagement respectively with the shoulders of said bolsters, said sleeve having a plurality of sets of diametrically alined key

receiving slots, each alined set of slots being disposed at a different elevation than the remaining sets of slots; and a key for connecting the sleeve and the pin, said key being engaged with the key slot of the pin and any one of said sets of diametrically alined slots of the sleeve.

In witness that I claim the foregoing I have hereunto subscribed my name this 17th day of December 1929.

STACY B. HASELTINE.
